UNITED STATES PATENT OFFICE.

CHESTER W. RICE, OF SCHENECTADY, NEW YORK, ASSIGNOR TO GENERAL ELECTRIC COMPANY, A CORPORATION OF NEW YORK.

SOUND-DETECTING DEVICE.

Application filed June 6, 1918. Serial No. 302,247.

My invention relates to devices for detecting sounds or similar vibrations transmitted through a fluid medium and is especially useful for detecting the sounds emanating from various sources such as submarine signal stations, submarine and other power propelled boats, or the like.

In carrying out my invention in practice, I may utilize a microphone, for example one of the inertia type, so arranged as to receive the vibrations from the fluid medium through an interposed body of a material such as soft rubber having non-resonant aperiodic characteristics. This body of soft rubber is in the form of a diaphragm which supports or carries the microphone and is preferably in an unstrained and unstretched condition. The sounds thereby collected by the microphone and rendered apparent to an observer by the use, in the ordinary way, of an electric telephone receiver, reach the observer free from distortion effects due to resonance, and unaccompanied by extraneous sounds of any kind produced in the apparatus itself. The sound thus rendered apparent is a faithful reproduction corresponding to the sound waves coming through the liquid or subaqueous medium to the device. The microphone is supported upon a soft rubber diaphragm to avoid the resonance effects which might occur if the microphones were supported on metal, wood or similar resonant material which would magnify certain sound vibrations and tend to produce a false quality in the sound perceived in the telephone receiver. For the purposes for which devices of this kind are commonly used a false reproduction or an alteration in quality of the sound received by the microphones is a serious fault.

The scope of my invention will be particularly pointed out in the appended claims, while the invention itself will be better understood by reference to the following description and the accompanying drawings, in which

Fig. 1 is a view in perspective of a device embodying my invention, while Fig. 2 is an enlarged sectional view of the same.

The sound receiving device made in accordance with my invention, though not necessarily limited to use under water is nevertheless adapted for that purpose, and to this end it is constructed so that its in-

terior working parts shall be maintained free from water or moisture. In the particular form indicated in the drawings a cup shaped member 1, best constructed of pure soft Pará rubber, contains the microphone element, which is carried on a perforated metallic disk 2 embedded in the rubber and having a perforated shank 3 projecting centrally into the interior or inner side of the cup. The rubber, which is molded about this perforated disk at the time the cup 1 is being formed, penetrates the openings or perforations in the disk 2 from side to side and thus firmly secures or sews it in place.

The microphone element is supported on the shank 3, which is centrally drilled and tapped to hold it. This microphone element, shown partly in section in Fig. 2, and in the main of usual construction, comprises a brass casing or cup 4 containing carbon granules 5 in contact with one carbon plate or terminal 6 resting on the bottom of the cup and also with a second carbon plate or terminal 7, electroplated on one side, and soldered on that side to a disk 8 of brass provided with a threaded projection 9. The carbon terminals are separated from the sides of the cup by a ring of felt 10, and the cup is closed by a perforated mica diaphragm 11 clamped between the disk 8 and a disk 12 of brass or other suitable material threaded on the projection 9 of the brass disk 8, and screwed down against the mica diaphragm. The brass casing or cup 4 has a threaded supporting stud 13 integral with or riveted to it to screw into the shank 3 and support the microphone in place.

To assist in making electrical connections to the microphone in such a manner that movement of the microphone does not cause variations of pressure on the carbon granules I provide a bail 14, of brass or other conducting material, fastened to a metal ring spun about the flaring lip of the cup 4 and in electrical contact through the cup with the carbon terminal 6. A flexible terminal wire 15 leading to the microphone is mechanically and electrically connected to the bail 14 while the other flexible terminal wire 16 is mechanically connected to but insulated from the bail by an insulated terminal 17, which is connected through a very flexible wire 18 to the threaded projection 9 and thence to the carbon plate or terminal 7.

To enclose the microphone in a water tight

chamber I close the open end of the rubber cup 1 with some suitable water tight closure. I prefer, as best shown in Fig. 2 of the drawing, a thimble or short tube 19 having external circumferential grooves and fitted tightly into the rubber cup 1. This thimble is counterbored at the outer end to receive various members which cooperate to produce a water tight closure, while the open inner end of the thimble leaves the bottom of cup 1 free to act as a diaphragm. A brass disk 20 fitting snugly in the counterbore of the thimble 19 has on its edge a groove for holding a drying agent, preferably metallic calcium in the form of a number of turns of wire 21. The slow diffusion of the air contained in the interior of the thimble and cup 1 through openings 22 into the groove 21 and over the calcium wire keeps the air perfectly dry.

Electrical connections with the microphone are made through the terminal wires 15 and 16 by leading-in wires 23 and 24 heavily coated with rubber 25 and 26 and fitting tightly into holes in the brass disk 20 and also into holes in a solid block 27 of soft rubber which presses against the grooved brass disk 20. To compress the rubber 27 firmly about the wires and against the disk I provide a follower disk 28, preferably of brass, and having holes for the wires. The follower disk is driven against the rubber block 27, expanding it outwardly against the thimble 19 and inwardly against the leading-in wires to form an absolutely water-tight joint, by means of a follower ring 29 screw threaded into the outer end of the thimble 19. A lock washer 30 of phosphor bronze or similar spring metal between the follower disk and the ring keeps the parts under constant compression in case they should have a tendency to give through the action of time or other influences.

In many cases it is advisable to clamp the rubber cup 1 to the thimble 19 by a clamp 31, locked by a screw fastener 32 in place around the cup so as strongly to compress it against the thimble.

By constructing the vibrating diaphragm as the base of a cup-shaped member and holding the diaphragm in place by clamping the side wall of the cup against the side wall of the tubular support 19, leakage past the edge of the diaphragm is prevented without squeezing of the edges of the diaphragm. Squeezing of the edges of the diaphragm would force the material thereof toward the center of the diaphragm and produce a loose, flabby construction which would interfere with proper sound transmission. Moreover, the location of the clamp away from the diaphragm permits a free adjustment of the edges of the diaphragm when the diaphragm is pressed into the tube by heavy water pressure.

To protect the leading-in conductors 23 and 24 and the other portions of the device projecting from the cup 1 a soft rubber cover 33, through which the leading-in conductors pass, is applied over the projecting portion 70 of the thimble 19. A reentrant portion 34 of this cover fits into the interior of the following ring 29.

When the device above described is immersed in a sound conducting liquid medium the sound waves act upon the bottom of the cup 1, which forms a rubber diaphragm for supporting the microphone, and cause vibrations to be transmitted to the carbon granules and carbon terminals by reason of 80 the inertia of the parts of the microphone. As already explained, the variations in resistance of the microphone circuit due to these sound vibrations may be disturbed, in case the device is used in the open sea, by 85 variations in the hydrostatic head of water above the device due to the rise and fall of the waves. The pressures due to water waves are applied and released very slowly, as compared with the rapid varying pressures produced by a sound wave, and cause a slow oscillation of the diaphragm, so that the microphone is moved bodily back and forth. Any effect upon the microphone of 90 this slow movement of the rubber diaphragm 95 is prevented by eliminating any factor which would make the microphone button sensitive to slowly applied pressure. To this end the terminal wires 14 and 15 leading to the microphone from the leads 23 and 24 are very flexible and are fastened mechanically to the bail 12 so that as the microphone is moved back and forth by the slow oscillation of the diaphragm these wires cause no variation in the pressure on the carbon granules of the 100 microphone.

Changes in air pressure in the closed chamber produced by the oscillations of the rubber bottom of the cup 1 also vary the pressure on the carbon granules if the casing 110 of the microphone is tight. To prevent these pressure variations the brass casing 4 may be ventilated by perforations 35 which equalize the pressure in the closed chamber, and in the casing 6.

I do not lay claim to the ventilated construction for the microphone as heretofore described nor to the use of the bail 14, as these features are described and claimed in companion applications of Albert W. Hull Serial No. 302,232 and Irving Langmuir Serial No. 302,279.

Sound detecting devices such as herein described may be used singly if desired, but are especially useful in pairs or in triplets, for determining the direction from which a sound comes by means of the binaural sense possessed by the human ears. When sound is transmitted to the human ears from a point which is not equally distant from the 115 120 125 130 135 140 145 150 155 160 165 170 175 180 185 190 195 200 205 210 215 220 225 230 235 240 two ears of the observer, the sound arrives at one ear later than at the other because of the different distances which the sound has to travel to reach the two ears. The 5 same sound impulses are therefore not received simultaneously at the two ears of the observer and in some way due to this effect the brain receives the impression that the source of sound is either at the one side 10 or the other of the observer. This effect is less pronounced the purer the quality of the sound received. In the case, for example, of a pure tone, such as that of a tuning fork, or a telephone receiver fed 15 with sine wave alternating current, the binaural sense can only with great difficulty determine the direction of the sound. Where, however, the sound includes sharp 20 peaks or other salient and recognizable variations or characteristics the binaural effect is much more acute. The use of a soft rubber diaphragm to support the microphone as heretofore described is of especial 25 value where devices of this general character are to be used binaurally, as it avoids any resonance effects such as might occur if diaphragms of metal, wood or the like were employed, which resonance effects would, by magnifying sound vibrations 30 forming no essential portion of the sounds to be listened to, have a tendency to produce a false quality in the sound perceived through the microphone. As the binaural 35 sense seems to depend upon some kind of comparison of some salient characteristics of the sound to be listened to, this sense is interfered with seriously where a false reproduction of the received sounds is produced by resonant effects produced in the 40 receiving apparatus itself.

While I have shown a microphone of the carbon granule type it is evident that microphones of other varieties may be employed as well as devices of any other character 45 such as magneto-phones or the like which will have the effect of producing variations in an electric current, in response to the vibrations of the rubber vibratory diaphragm herein shown. While other material having the desired characteristics of 50 soft rubber may be employed in place thereof, soft rubber gives the best results for the purposes in hand of any material with which I am acquainted.

It is to be observed that in the device 55 which I have disclosed the rubber diaphragm supporting or carrying the microphone is in an unstrained and unstretched condition and I consider this a valuable 60 quality. The fact that rubber is of approximately the same density as water, in which it is immersed, contributes to the non-resonant quality of the diaphragm under the conditions of use.

The diaphragm upon which the micro-

phone is mounted should be very thick to secure the best results. As shown in Fig. 2, the thickness of this diaphragm is about three-fourths of the clear distance between its opposite points of support. It has been 70 found in practice that such a diaphragm is less resonant, that is, it has a less pronounced natural period of vibration, than a thin diaphragm in which the thickness might be one-fifth of the distance between 75 the opposite points of supports, or less. This more perfect aperiodic quality of the thick diaphragm is believed to be due to the large volume of material throughout which the energy of vibration is dissipated, and to the 80 fact that the thick diaphragm acts as a beam in resisting the water pressure and in responding to the sound vibrations. A thin diaphragm, when made of rubber or any similar material, would be pressed so far 85 into the tube 19 by the water pressure when submerged to the depth at which these devices are ordinarily used, as to have the shape of a deep inverted dome. The water pressure would be resisted entirely by the 90 tensile stresses engendered as the result of the stretching of the material of the diaphragm. The material of the thin deep inverted dome would be in tension throughout. In the thick diaphragm, on the other 95 hand, the heavy water pressure is ordinarily insufficient to crowd the whole bulk of the diaphragm into the supporting tube. The water pressure is resisted by the shearing 100 stresses and compressive stresses which are engendered in the diaphragm after the manner in which stresses are engendered in a beam. But, whatever the explanation may be, it has been very clearly established that the thick diaphragm such as shown in Fig. 105 2, which was regularly used for the detection of submarines during the war, was less resonant, more aperiodic, and generally more efficient than thin diaphragms. The 110 advantages of the thick diaphragm became very apparent at depths of fifteen feet and upward.

What I claim as new and desire to secure by Letters Patent of the United States is:

1. The combination of a body of rubber having a recess therein with one wall proportioned to transmit sound vibrations, means for closing said recess against the access of water, electrical conductors communicating with said recess and a microphone mounted on said wall of said rubber body to respond to sound vibrations transmitted through said rubber wall.

2. A sound detecting device comprising a 125 wall of soft rubber completely enclosing a space, a portion of the enclosing soft rubber wall being adapted to vibrate in response to sound vibrations, a current varying device mounted on said vibratory portion of the 130

- enclosing wall, and conductors of electric current connected to said current varying device.
3. The combination of a rigid tubular member open at both ends, soft rubber cups upon the ends of said tubular member, a portion of one of said cups constituting a vibratory diaphragm, a device mounted upon said diaphragm for varying an electric current in response to vibrations of said diaphragm, electrical conductors extending through the other cup and connected to said current varying device.
4. In combination, water tight casing, a thick diaphragm forming a portion of the wall of said casing, said diaphragm being composed of material which has substantially the damping characteristics of soft rubber, a device supported upon said diaphragm for causing variations in an electrical current corresponding to vibrations of said diaphragm, and electrical conductors leading to and connected with said current varying device.
5. In combination, a water tight casing, a soft rubber diaphragm forming a portion of the wall of said casing, the thickness of said diaphragm being more than one fifth of its diameter, and said diaphragm having a substantial portion thereof under compression when submerged to considerable depths, a microphone supported upon said diaphragm, and electrical conductors leading to and connected with said microphone.
6. In combination, a water tight casing, a diaphragm forming a portion of the wall thereof, said diaphragm formed of a material which has substantially the same vibratory qualities as soft rubber, means for supporting said diaphragm with a portion thereof free for vibration, the thickness of the diaphragm being more than one-fifth as great as the distance between its opposite points of support, a microphone in said casing mounted on said diaphragm, electrical conductors extending into said casing and connected to said microphone.
7. A vibration detector comprising a diaphragm of soft rubber and means for supporting the same for vibration in response to sound vibrations, a current varying device supported upon said diaphragm, the thickness of said diaphragm being approximately as great as three-fourths of the diameter of its vibrating portion.
8. A vibration detector comprising a casing having an aperture therein, a rubber diaphragm closing and sealing such aperture, a bushing member embedded in the diaphragm, a current-varying device, and means for attaching the current-varying device to the bushing member so that the current-varying device is supported within the casing upon the rubber diaphragm.
9. A vibration detector for use under water, comprising a water free chamber, a rigid tubular member, and a cup composed of a material which has substantially the same vibratory qualities as soft rubber, the cup being mounted upon an open end of the tubular member so that the bottom of the cup constitutes a portion of the wall of the water free chamber, and the side wall of the cup closely engaging the side wall of the tubular member to hold the cup in place.
10. A vibration detector for use under water, comprising a water free chamber, a rigid tubular member, and a thick-walled cup composed of a material which has substantially the same vibratory qualities as soft rubber, the cup being mounted upon an open end of the tubular member so that the bottom of the cup constitutes a portion of the wall of the water free chamber, and a clamp binding the side wall of the cup upon the side wall of the tubular member to hold the cup in place.
11. A vibration detector for use under water, comprising a water free chamber, a rigid tubular member, and a cup having a thick bottom, composed of a material which has substantially the same vibratory qualities as soft rubber, the cup being mounted upon an open end of the tubular member so that the bottom of the cup constitutes a portion of the wall of the water free chamber, a clamp binding the side wall of the cup upon the side wall of the tubular member to hold the cup in place, a current-varying device mounted upon the bottom of the cup, and electrical conductors connecting with said current-varying device.
12. A vibration detector comprising a casing having an aperture therein, a rubber diaphragm closing and sealing such aperture, a bushing member embedded in the diaphragm, and a current-varying device having a threaded member engaging the bushing to support the current-varying device within the casing.

In witness whereof, I have hereunto set my hand this 5th day of June, 1919.

CHESTER W. RICE.
